US00D759634S

(12) **United States Design Patent**
Brunner et al.

(10) **Patent No.:** **US D759,634 S**
(45) **Date of Patent:** **** Jun. 21, 2016**

(54) **AUDIO LISTENING SYSTEM**(71) Applicant: **Apple Inc.**, Cupertino, CA (US)(72) Inventors: **Robert Brunner**, San Francisco, CA (US); **Rhys Bonahoom**, Burlingame, CA (US)(73) Assignee: **Apple Inc.**, Cupertino, CA (US)(***) Term: **15 Years**(21) Appl. No.: **29/527,763**(22) Filed: **May 21, 2015****Related U.S. Application Data**

(63) Continuation of application No. 29/493,738, filed on Jun. 12, 2014, now Pat. No. Des. 732,509, which is a continuation-in-part of application No. 29/441,335, filed on Jan. 3, 2013, now Pat. No. Des. 707,652.

Primary Examiner — Paula Greene(74) *Attorney, Agent, or Firm* — Sterne, Kessler, Goldstein & Fox P.L.L.C.(57) **CLAIM**

The ornamental design for an audio listening system, as shown and described.

DESCRIPTION

FIG. 1 is a front perspective view of an audio listening system showing our new design;

FIG. 2 is a rear view thereof;

FIG. 3 is a front view thereof;

FIG. 4 is a left side perspective view thereof;

FIG. 5 is a left side view thereof; and,

FIG. 6 is a right side view thereof.

The broken lines in the Figures show portions of the audio listening system that form no part of the claimed design.

1 Claim, 2 Drawing Sheets(56)
